Primary Examiner — Katrina N Gonzalez

(57) **CLAIM**

The ornamental design for a drying box for pet as shown and described.

DESCRIPTION

FIG. 1 is a bottom perspective view of a drying box for pet, showing my new design;

FIG. 2 is a top perspective view thereof;

FIG. 3 is a bottom plan view thereof;

FIG. 4 is a top plan view thereof;

FIG. 5 is a left elevation view thereof;

FIG. 6 is a right elevation view thereof;

FIG. 7 is a front elevation view thereof;

FIG. 8 is a rear elevation view thereof;

FIG. 9 is another perspective view thereof, but shown in folded configuration; and,

FIG. 10 is another perspective view thereof shown in folded configuration.

The broken lines in the drawings illustrate portions of the drying box for pet which form no part of the claimed design.
